UNITED STATES PATENT OFFICE.

ALFRED W. BRUCE, OF NEW YORK, N. Y.

LOCOMOTIVE BOILER.

Application filed January 27, 1927. Serial No. 164,030.

My invention relates to boilers of the locomotive type, and of the class thereof in which the sides of the fire box and combustion chamber are formed of a plurality of water tubes, instances of which are exemplified in the patent of J. M. McClellon, No. 1,580,063, dated April 6, 1926, and in the patent of myself, No. 1,624,655, dated April 12, 1927. My present invention is particularly directed to the adaptation of a boiler of the type specified, for operation under comparatively high steam pressure, and to effecting a reduction of the weight and dimensions of the boiler to a substantial extent.

The improvement claimed is hereinafter fully set forth.

In the accompanying drawings: Figure 1 is a vertical longitudinal central section, through a boiler embodying my invention; Fig. 2, a partial similar section thereof, illustrating a structural modification; Fig. 3, a vertical transverse section, the right hand half being taken on the line III, III of Fig. 1, and the left hand half on the line III^a, III^a thereof; Fig. 4, a similar section, the left hand half being taken on the line IV, IV of Fig. 1, and the right hand half on the line IV^a, IV^a thereof; Fig. 5, a similar section, the right hand half being taken on the line V, V of Fig. 1, and the left hand half being taken on the line V^a, V^a, thereof; Fig. 6, a vertical longitudinal central section through a boiler, illustrating a structural modification; Fig. 7, a vertical transverse section, the right hand half being taken on the line VII, VII of Fig. 6, and the left hand half on the line VII^a, VII^a thereof; Fig. 8, a similar section, the right hand half being taken on the line VIII, VIII of Fig. 6, and the left hand half on the line VIII^a, VIII^a thereof; Fig. 9, a similar section, on the line IX, IX of Fig. 6; Fig. 10, a side view, in elevation, of means for promoting circulation; and Fig. 11, a front view of the same.

In the practice of my invention, referring descriptively to the specific embodiment thereof which is herein exemplified, and first to Figs. 1 to 5 inclusive, the improved locomotive boiler thereof comprises three main sections; the fire box section, A; the barrel section, B, through which extends a plurality of fire tubes; and the smoke box section, C, and a combustion chamber, D, is located in the forward portion of the fire box section. The fire tubes, 3^b, of the barrel section, extend from the front sheet of a forward header, 12,

to the back sheet of a rear header, 13, said headers constituting the front and rear ends, respectively, of the barrel section. Each of the fire tubes, 3^b, is surrounded by a water tube, 3^c, said water tubes extending from the rear wall of the forward header, 12, to the front wall of the rear header, 13, and thereby establishing communication between the water spaces of said headers. The superheating elements, 18^a, of the superheater, 18, are located in the fire tubes, 3^b.

The mud ring, 2, of the fire box, is hollow, and forms the bottom support of a plurality of fire tubes, 3, which are set closely together, forming the side walls of the fire box, and are connected, at their upper ends, with a drum, 4, which extends horizontally and forwardly, from the back head, 5, of the boiler, through which it passes, to a communication with the barrel section, in this instance, through the forward header, 12, to which its forward end is open. The mud ring, 2, at its rear end, supports and communicates with, the back head, 5. Arch tubes, 6, which support a fire brick arch, 7, are connected to the front of the mud ring, and extend upwardly and rearwardly to the back head, 5. The upper surface of the grate, 8, lies approximately in the plane of the top of the mud ring. The forward limb of the mud ring is apertured for communication with a feed water connection, 11, leading into the barrel section, B, to the forward portion of which, water is supplied through a feed pipe (not shown) provided with a check valve, in the ordinary manner.

The water tubes, 3^a, of the combustion chamber, D, form continuous walls with the fire box water tubes, 3, and conform in curvature therewith, above the axial line of the barrel, below which they are curved on arcs struck substantially radially from said axial line. The water tubes, 3 and 3^a, are connected, at their tops, to the drum, 4, and, at their bottoms, to the mud ring, 2, and to the feed water connection member, 11, respectively. The member, 11, extends forwardly to a connection with the barrel section, B, shown in Fig. 1 as being through the rear header, 13, and provides a water passage from said barrel section to the bottoms of the combustion chamber water tubes, 3^a. The drum, 4, extends through both the headers, 12 and 13, but is in communication with the rear header, 12, only, through a passage, 4¹, at its top. Two smaller drums, 4^x, 4^y, are disposed

on the opposite sides of the drum, 4, exterior to the barrel, said smaller drums extending from the header, 12, to the header, 13, and being in communication with the barrel through said headers.

A suitable throttle valve, 16, is located adjacent to the front of the drum, 4, and controls communication between said drum and steam supply pipes, 17, leading therefrom to 10 a superheater, 18, or to the valve chests of a locomotive, as the case may be.

Fig. 2 illustrates a structural modification in which the water connection member, 11, is extended forwardly, by an extension section, 11^a, and communicates with the barrel, B, through said extension section, which is open to the forward header, 12.

In the operation of a boiler of the construction hereinbefore specified, steam generated 20 in the back head, 5, and side water tubes, 3 and 3^a, flows forwardly through the drum, 4. Steam generated in the barrel section, B, rises through the header, 13, into the drum, 4, through the passage, 4¹, and flows forwardly 25 to the steam collector chamber, 4^f, hereinafter described. There is thus a flow of steam forwardly from the water tube walls of the fire box, through the drum, 4, to the throttle valve, 16, and a flow of steam from the barrel section, through the drum, 4, to the throttle valve. Steam from both sources, traverses 30 past the throttle valve, through the pipes, 17, to the superheater, 18, or directly to the valve chests of the locomotive. There is likewise 35 an independent circulation in the barrel section, from the rear to the forward ends thereof, through the lateral drums, 4^x, 4^x.

A wrapper sheet, 20, which encircles and 40 houses the fire box and the combustion chamber, is secured to the header, 13, the back head, 5, and the mud ring, 2, said wrapper sheet performing, as in the construction set forth in my Letters Patent No. 1,624,655 aforesaid, primarily the function of a rigid 45 connecting member for the fire box and boiler barrel section, and secondarily, that of a closure or housing for the top of the fire box, to prevent the escape of gases of combustion therefrom. Suitable lagging or insulating 50 material, 21, is applied, between the outsides of the water tubes, 3 and 3^a, and the wrapper sheet.

Boilers embodying my invention present 55 the advantage of decreasing the size of the barrel section, B, with a resultant reduction in weight; the elimination of structural difficulties and increase in the factor of safety; and the provision of separate circulation systems for the fire box and the barrel section, thereby increasing the rapidity of circulation 60 and mechanically controlling the circulation to prevent interference of the water circuits, all of which features effect a substantial increase in efficiency. The boiler is of a form adapted for carrying the highest steam pres-

sures now utilized in service or contemplated in locomotive operation.

Figs. 6 to 11 inclusive, illustrate a structural modification, in which, as in the instance first described, the barrel section, B, 70 of the boiler, is composed of a forward header, 12, a rear header, 13, a plurality of fire tubes, 3^b, extending through the headers from the front sheet of the forward header to the back sheet of the rear header, and a 75 plurality of water tubes, 3^c, surrounding the fire tubes and extending from the back sheet of the forward header to the front sheet of the rear header. This construction is similar to that before described, and illustrated 80 in Figs. 1 to 5, inclusive, but differs therefrom in that the drum, 4, extends forwardly only sufficiently far to enable a communication to be made between it and the rear header, 13, which communication is effected through the 85 steam supply passage, 4¹, at its top. The forward end of the drum is open, and is connected to an upwardly and forwardly extending junction piece, 4^a.

A water circulation pipe, 4^c, leads from 90 the lower end of the junction piece, 4^a, to the forward header, 12. A steam receiving chamber, 4^e, (one or more), of smaller diameter than the drum, extends forwardly from the upper end of the junction piece, to or near 95 the rear of the smoke box, C, its forward end being supported on, and fitted to slide in, a bearing, 4^h, which is shown as secured to the forward header, 12, but may, if preferred, be connected to the smoke box. Longitudinal expansion of the chamber, 4^e, is 100 thereby provided for. A steam collecting chamber, 4^f, having a plurality of perforations in its top, is located in the steam receiving chamber, 4^e, adjacent to its top and to its 105 forward end. By this construction, the steam is separated as far as possible from the water, and it is delivered from the chamber, 4^f, to the throttle valve, 16, and thence to the superheater, 18, or to the engine cylinders, as the case may be. 110

A feed water member, 11, which, as in the instance first above described, is a lower water drum, extends forwardly through the combustion chamber, D, said member being 115 secured, at its rear end, to the front of the mud ring, 2, and passing freely through the back sheet of the rear header, 13, with which it makes a sliding joint, thereby providing 120 for its expansion under the influence of heat. The feed water member communicates, at its forward end, with the barrel section, through upwardly extending water circulation pipes, 22. Arch tubes, 6, extend upwardly and 125 rearwardly from the front of the mud ring, and support a brick arch, 7, in the ordinary manner. Instead of being directly connected to the feed water member, 11, the circulation pipes, 22, may, as shown in Figs. 10 and 11, lead to the inlets of a centrifugal pump, 130

24; the outlets of which communicate with the member, 11. By this construction, the natural continuous automatic water circulation through the boiler may be promoted and expedited when desired. Feed water is supplied to the barrel, B, through a feed pipe, (not shown) provided with a check valve, in the ordinary manner.

In the operation of the structural modification above described, there is a single continuous positively guided circulation of water through the water spaces of the barrel and fire box, the water in the barrel being thereby constantly stirred up, instead of being comparatively undisturbed as in ordinary constructions. The water supplied to the barrel moves to the rear header; thence downwardly through the circulation pipes, 22, to the feed water member, 11, and mud ring; thence, through the side water tubes, to the drum, 4, and thence, through the circulation pipe, 4^c, to the forward portion of the barrel. The circuit continuously repeats itself through the members stated.

25 I claim as my invention and desire to secure by Letters Patent:

1. In a boiler of the locomotive type, the combination of a fire box, the sides of which are formed of water tubes; a barrel, extending forwardly from the forward end of the firebox; forward and rear barrel section headers; a drum, extending forwardly from the rear end of the fire box and communicating with the side water tubes thereof and with the forward header; water tubes, connecting the water spaces of the headers; fire tubes, extending through said water tubes and through the headers, and providing water spaces between themselves and said water tubes; and means for supplying water from the barrel to the side water tubes of the fire box.

2. In a boiler of the locomotive type, the combination of a fire box, the sides of which are formed of water tubes; a barrel, extending forwardly from the forward end of the fire box; forward and rear barrel section headers; a drum, extending forwardly from the rear end of the fire box, and communicating with the side water tubes thereof, and with the forward header; water tubes, connecting the water spaces of the headers; fire tubes, extending through said water tubes and through the headers, and providing water spaces between themselves and said water tubes; and a lower water drum extending rearwardly from the rear header, and communicating therewith, and with side water tubes of the fire box.

3. In a boiler of the locomotive type, the combination of a fire box, the sides of which are formed of water tubes; a barrel, extending forwardly from the forward end of the fire box; a hollow mud ring, communicating with said water tubes; forward and rear barrel section headers; a drum, extending

forwardly from the rear end of the fire box and communicating with the side water tubes thereof and with the forward header; water tubes, connecting the water spaces of the headers; fire tubes, extending through said water tubes and through the headers, and providing water spaces between themselves and said water tubes; and a lower drum, extending from the rear header to the mud ring, and communicating with the said header and said mud ring and with side water tubes of the fire box.

4. In a boiler of the locomotive type, the combination of a fire box, the sides of which are formed of water tubes; a barrel, extending forwardly from the forward end of the fire box; forward and rear barrel section headers; a drum, extending forwardly from the rear end of the fire box, and communicating with the side water tubes thereof and with the forward header; water tubes, connecting the water spaces of the headers; fire tubes, extending through said water tubes and through the headers, and providing water spaces between themselves and said water tubes; a lower drum, extending forwardly from the mud ring, and communicating therewith, with the side water tubes of the fire box, and with the rear header; and a bearing on the rear header in which said drum is fitted freely.

5. In a boiler of the locomotive type, the combination of a fire box, the sides of which are formed of water tubes; a barrel, extending forwardly from the forward end of the fire box; forward and rear water barrel section headers; a drum, extending forwardly from the rear of the fire box and communicating with the side water tubes thereof, with the rear header, and with a mud ring; water tubes, connecting the water spaces of the headers; fire tubes, extending through said water tubes and providing water spaces between themselves and said fire tubes; a junction piece, communicating with the forward end of the drum; a steam receiving chamber, extending forwardly from the junction piece; means for delivering steam from said chamber to engine cylinders; and a water circulation pipe, leading from the junction piece to the forward header.

6. In a boiler of the locomotive type, the combination of a fire box, the sides of which are formed of water tubes and the forward portion of which is a combustion chamber; a barrel, extending forwardly from the forward end of the fire box; a mud ring; forward and rear barrel section headers; tubes, connecting said headers; an upper drum, extending forwardly from the rear end of the fire box section, and communicating with the side water tubes thereof and with the barrel section; a lower drum, connected to the mud ring; and a water circulating connection between the upper and lower drums.

7. In a boiler of the locomotive type, the combination of a fire box, the sides of which are formed of water tubes and the forward portion of which is a combustion chamber; a barrel, extending forwardly from the forward end of the fire box; a mud ring; forward and rear barrel section headers; tubes, connecting said headers; an upper drum, extending forwardly from the rear end of the fire box and communicating with the side water tubes thereof and with the barrel section; a lower drum, connected rigidly to the mud ring, and having its forward end sliding freely in a bearing at its front end; and a water circulating connection between the upper and lower drums.
8. In a boiler of the locomotive type, the

combination of a fire box, the sides of which are formed of water tubes and the forward portion of which is a combustion chamber; a barrel, extending forwardly from the forward end of the fire box; a mud ring; forward and rear barrel section headers; tubes, connecting said headers; an upper drum, extending forwardly from the rear end of the fire box and communicating with the side water tubes thereof and with the barrel; a lower drum, connected to the mud ring; a water circulating connection between the upper and lower drums; and mechanically operable means for promoting circulation through the boiler structure.

ALFRED W. BRUCE.
